UNITED STATES PATENT OFFICE.

JAMES W. LAWSON, OF EAST PROVIDENCE, ASSIGNOR TO HANCOCK,
BECKER & CO., OF PROVIDENCE, RHODE ISLAND.

DESIGN FOR A GEM-SETTING.

SPECIFICATION forming part of Design No. 19,153, dated June 11, 1889.

Application filed April 26, 1889. Serial No. 308,759. Term of patent 7 years.

To all whom it may concern:

Be it known that I, JAMES W. LAWSON, a citizen of the United States, residing at East Providence, in the county of Providence, in the State of Rhode Island, have invented and produced a new and original Design for a Gem-Setting, of which the following is a specification, reference being had to the accompanying drawings.

10 Figure 1 is a perspective view of my invention. Fig. 2 is a side elevation, and Fig. 3 is a top plan, of the same.

15 My invention is a design for the setting of gems for rings, brooches, and other articles of jewelry; and it consists of a circular ring with a series of prongs mounted thereon, which prongs are lanceolate in external outline and are united to each other at their bases by a curved portion, which touches said ring, and 20 they have an inner triangular opening, within which space spurs from said ring project up centrally.

In the drawings, A represents the circular ring or base.

25 B B are the prongs to hold the jewel within their apexes. These prongs in their side elevation are nearly triangular, and in front elevation they are lance-shaped and are open internally. The open space thus formed by the

30 sides of the prong and the base A is triangular, and in the center of said space a spur C rises from the base A. Each spur is itself substantially triangular both in side elevation and on its upper inclined edge. The prongs B at their respective bases have a 35 curved shape to form them into a continuous pattern. Said curved portions, as also the lower front edge of the spurs C, are beveled toward the base A, while the upper front edges of both the prongs and the spurs are concaved. 40 The prongs are set around the ring, so as to form in top plan a six-pointed star, the spurs being placed intermediately as rays.

What I claim is—

45 The design for gem - settings herein described and shown, consisting of a circular base A, the open lanceolate prongs B B, having the front edge thereof beveled and concaved, as shown, and formed with intermediate curves at their adjacent bases, and the 50 concaved and beveled triangular spurs C, projecting from said base A into the opening of said prongs B, respectively, as set forth.

JAMES W. LAWSON.
